No. 5,711,119.

UNITED STATES PATENT OFFICE.

HARLEY A. FRIEND, OF ZION CITY, ILLINOIS.

NOTCHED-LEAF BOOK.

1,199,170.

Specification of Letters Patent. Patented Sept. 26, 1916.

Application filed January 17, 1916. Serial No. 72,411.

To all whom it may concern:

Be it known that I, HARLEY A. FRIEND, a citizen of the United States, and a resident of Zion City, county of Lake, and State of Illinois, have invented certain new and useful Improvements in Notched-Leaf Books, of which the following is declared to be a full, clear, and exact description.

This invention relates to duplicate leaf books of account, such as are used in the usual course of business for making original and duplicate entries, as for instance receipts, memoranda and the like, and the primary object of this invention is to provide simple means for locating the uppermost unused original leaf of the book, whereby the user may instantly turn to said uppermost unused leaf to make the necessary entry thereon.

This invention consists in the novel features hereinafter fully set forth and claimed.

This invention is clearly illustrated in the drawing accompanying this specification, in which:

Figure 1, is a perspective view of a duplicate leaf account book, embodying a simple form of the present invention, one of the covers being thrown back; Fig. 2, is a perspective view of said account book, showing one of the covers thrown back and a plurality of the leaves thereof spread apart to more clearly illustrate the invention, and Fig. 3, is a perspective view of the book from which a number of the original sheets have been detached.

Referring to said drawing, the reference numerals 10, 11, designate the two covers of the book, 12, the detachable leaves upon which the entries are made, and which may be designated as the original leaves, and 13, designates the permanently bound leaves upon which the duplicates are made. Said originals and duplicates alternate with each other, and are bound with the covers in the usual manner. The original leaves 12, are formed with lengthwise extending score lines or rows of perforation 14, and also with transverse score lines or rows of perforations 15, to provide individual detachable slips upon which the entries are made, each slip being detached from the remainder after an entry has been made thereon, and delivered to the customer or purchaser. The said slips, as well as the duplicate leaf may have suitable printed matter and blank spaces

thereon, which are to be filled in, said printed matter depending of course upon the character of entries to be made.

The duplicating leaves 13, are formed with notches 16, in one edge, which notches are located at or below the lowermost score lines or rows of perforation 15; said notches are located in alinement with each other so that when any number of detachable slips have been removed, a single notch to all intents and purposes will always be presented, which notch extends to the uppermost unused detachable slip or leaf, upon which the original entries are to be made.

In Fig. 1, the first original leaf in the book is seen partly raised, and immediately below the same is the first duplicate leaf of the book. In opening the cover, the first leaf is immediately exposed to view, and entries may be made upon each of the slips thereof, one after the other, and said slips may be detached one after the other and handed to the customers or purchasers. A carbon or other transfer sheet is placed between the original leaf and the duplicate in order that a duplicate of the entry may be made upon the duplicate sheet. After all of the slips of the first original leaf have been detached, the uppermost original leaf is located immediately below the first duplicate leaf upon which entries have been made, and to turn to this uppermost original leaf all that is necessary for the user to do is to place his thumb upon the exposed part of the original leaf appearing through the notch 16, and then turn back the first duplicate leaf, thus exposing the uppermost unused leaf. It will thus be seen that regardless of how many of the original leaves have been detached from the book, the uppermost unused leaf is exposed through the notches in the duplicate leaves thereabove. This is particularly shown in Fig. 3, where a number of original leaves have been detached and a group of the duplicate leaves are shown as raised slightly above the uppermost unused leaf.

If desired, entries may be made not only on duplicate leaves but on triplicate leaves, and the originals and duplicates may have the lines of perforations whereby they may be detached, and the triplicate copies which are not to be detached from the book may be provided with the notches as above set forth. In fact, it is quite possible to provide a book

wherein any desired number of copies may be made with the original entry, the last copy of which is the one permanently bound in the book, and the one in which the notch is formed.

5 I claim as new and desire to secure by Letters Patent:

1. A notched leaf book, comprising alternating original and duplicate leaves, the 10 original leaves having lengthwise and crosswise extending lines of perforations, dividing said leaves into a plurality of detachable slips, and the duplicate leaves being permanently bound in the book, each duplicate 15 leaf having a notch in its edge located be-

low the lowermost detachable slips of the original leaves.

2. A notched leaf book, comprising alternating original and duplicate leaves, the original leaves having a lengthwise extending line of perforation and a plurality of crosswise extending lines of perforation dividing said leaves into a plurality of detachable slips and the duplicate leaves being permanently bound in the book, and each 20 duplicate leaf having a notch in its edge located below an endmost detachable slip of the original leaves.

H. A. FRIEND.

Copies of this patent may be obtained for five cents each, by addressing the "Commissioner of Patents,
